(57) **CLAIM**

The ornamental design for robotic exoskeleton suit for lifting loads as shown and described.

DESCRIPTION

1. Robotic exoskeleton suit for lifting loads

1.1: Perspective

1.2: Front

1.3: Back

1.4: Left

1.5: Right

1.6: Top

1.7: Bottom

1.8: Rear perspective focusing on the bottom portion of the design

1.9: Enlarged view of rear perspective focusing on bottom portion

Reproduction 1.1 is a perspective view of a robotic exoskeleton suit for lifting loads showing our new design; reproduction 1.2 is a front elevation view thereof; reproduction 1.3 is a rear elevation view thereof; reproduction 1.4 is a left side elevation view thereof; reproduction 1.5 is a right side elevation view thereof; reproduction 1.6 is a top plan view thereof; reproduction 1.7 is a bottom plan view thereof; reproduction 1.8 is a rear perspective focusing on the bottom
